UNITED STATES PATENT OFFICE.

ALVA WILLIAMSON, OF ATLANTIC, IOWA.

SOUNDING HORNS.

1,017,938.

Specification of Letters Patent. Patented Feb. 20, 1912.

Application filed March 29, 1910. Serial No. 552,188.

To all whom it may concern:

Be it known that I, ALVA WILLIAMSON, a citizen of the United States, and a resident of Atlantic, in the county of Cass and State 5 of Iowa, have invented certain new and useful Improvements in Sounding Horns, of which the following is a specification, reference being had to the accompanying drawings.

10 The object of my invention is to provide simple, durable and inexpensive means, whereby the intermittent exhaust from an explosive engine may be utilized to operate a wind instrument such as a horn in a continuous, even, and uniform manner and also to provide convenient means whereby an operator may, by foot pressure, open the valves for permitting the wind instrument to be sounded.

20 My invention consists in the construction, arrangement and combination of an explosive engine, of means whereby the objects contemplated may be attained, as herein-after more fully set forth, pointed out in 25 my claims and illustrated in the accompanying drawings, in which:

Figure 1 shows a side view of my invention used in connection with an automobile which is shown in dotted outline. Fig. 30 2 shows an enlarged, detail, side view of an apparatus embodying my invention. Fig. 3 shows a similar view, partly in section. Fig. 4 shows an enlarged, detail, sectional view of the valve device for opening and 35 closing the passageway leading to the storage chamber, and illustrating a modification. Fig. 5 shows a side view of a device embodying my invention applied to a launch, the outline of the latter being indicated by dotted lines, and Fig. 6 shows a side view of a device embodying my invention illustrating a modification.

Referring to the accompanying drawings, I have used the reference numeral 1 to indicate the exhaust pipe of an explosive engine. Communicating with the exhaust pipe is a T-connection 3 and communicating with one branch of this T-connection is a pipe 2 leading to a muffler 4 of ordinary construction. Communicating with another branch of the T-connection 3 is a duplex valve casing 5 having valve seats at both

ends. Slidably mounted within the valve casing 5 is a valve stem 10 having a valve 6 at one end and another valve 7 at the other 55 end. I provide for supporting the valve stem within the casing by means of two guide devices 10'. By this arrangement it is obvious that when the valves are in the position shown in Fig. 3, all of the exploded 60 gases passing through the exhaust pipe 1 will be directed through the muffler but when the valves are at their opposite limit of movement some of the exploded gases passing through the muffler will enter the 65 interior of the valve casing 5 and be deflected downwardly through a pipe 15 at the center of the casing, the outer end of the casing being closed by the valve 7.

I provide for normally holding the valves 70 in the position shown in Fig. 3 by means of a contractile coil spring 12 attached to the projecting end of the valve stem 10. In order to provide for opening the valve to permit the passage of the exploded gases 75 through the pipe 15, I have provided a lever 11 fulcrumed to a suitable support and connected to the valve stem. This lever is provided with a rod 13, which rod is attached to a foot lever 14 so that, by the operator 80 pressing his foot upon the lever 14, the pressure of the spring 12 may be overcome and the valves within the casing 5 may be held to position for permitting some of the discharge of the explosive engine to 85 pass into the pipe 15. Arranged in the pipe 15 is a check valve 16 of ordinary construction designed to freely permit the passage of exploded gases through the pipe 15 and to prevent them from passing back, 90 Communicating with the check valve 16 is a pipe 17 which leads to a cylindrical tank 18. This tank is divided into two compartments; the compartment 19 forming a compression chamber and the compartment 95 20 forming an expansion chamber to which one or more wind instruments such as horns 22 may be connected. Between the chambers 19 and 20 is a by-pass having a valve 21 therein, whereby the amount of exploded 100 gases passing through the compression chamber to the expansion chamber may be regulated at the will of the operator.

In the modification illustrated in Fig. 4, I

have provided means whereby all of the burned gases passing through the exhaust pipe will be directed into the storage chamber to thereby increase the capacity of the wind instruments. The modification consists of a sliding hood 37 attached to the valve stem 10 and so arranged that when the valve is moved to its limit of movement toward the right, as shown in said figure, the hood will completely close the portion of the T-connection that extends to the muffler while permitting the entire quantity of burned gases passing through the exhaust pipe to enter the valve casing 5.

15 In the modified form shown in Fig. 6, the storage and escape chambers are indicated by the reference symbol 18. They are provided with a by-pass and controlling valve indicated by the symbol 21. A number of bosses are shown on the escape chamber to indicate where the sounding horns may be attached. The muffler is indicated by the symbol 4 and has an escape pipe 1 admitted into it. Leading from the muffler is the 20 duplex valve casing 5 and extended from this casing is the pipe 15 provided with a check valve 16 which also communicates with the pipe 17 leading to the cylindrical tank 18. Within the pipe 16 is a puppet valve B of ordinary construction by which the burned gases may be discharged when the pressure thereon exceeds a certain predetermined amount. By means of this 25 puppet valve B I provide for automatically regulating the pressure within the storage chamber 19 and I so arrange the other parts that an excessive amount of the burned gases under pressure will be delivered through the pipe 17, the surplus escaping 30 through the puppet valve B.

40 In the modified form shown in Fig. 5, I have illustrated a launch by dotted lines indicated by the reference symbol 13'. The remaining parts are the same as hereinbefore described except that I employ a whistle 26 applied to the exhaust chamber 20 instead of the horns shown in the other forms of the invention.

45 In practical operation and assuming that the explosive engine is running and that the exhaust therefrom is passing through the pipe 1, it is obvious that when the valve 6 is in its closed position all of the burned gases will pass through the muffler in the ordinary manner. However when the operator manipulates the foot lever 14 part of the products of combustion will pass through the pipe 15 into the storage chamber. The check valve 16 will prevent a back pressure 55 upon the pipe 15 and retain burned gases under pressure in the chamber 19. This gas under pressure in the chamber 19 may pass out slowly through the valve 21 into the exhaust chamber and from thence into the 60 wind instrument. By this arrangement I

am enabled to obtain a continuous, uniform and steady flow of burned gases through the wind instrument to produce a uniform, even sound which may be continued indefinitely so long as the engine is running.

70

The particular form of the duplex valve is not essential to the successful operation of my invention as it is obvious that various other means may be employed for directing all or part of the burned gases under pressure into the storage chamber. It is obvious however that if desired all of the burned gases from the explosive engine may be delivered to a pipe 15 and a puppet valve B may be applied thereto to permit the escape 80 of the surplus burned gases under pressure and to thereby maintain a uniform pressure within the storage chamber.

75

I claim as my invention:

1. In a device of the class described, the combination of an engine exhaust pipe, an inelastic gas storage receptacle in communication with the exhaust pipe, said exhaust pipe being provided with an outlet other than the one leading to the storage receptacle, a manually operated valve device whereby the exhaust gases may be directed either into the storage receptacle or through the said outlet, a check valve interposed between the exhaust pipe and the storage receptacle to prevent the flow of gas from the storage receptacle to the exhaust pipe, a pressure equalizing receptacle, there being a restricted passageway provided between said receptacle and the storage receptacle, and a wind instrument operatively connected with the equalizing receptacle, the passageway from the equalizing receptacle to the wind instrument being unobstructed, whereby gas under fluctuating pressure in the exhaust pipe may either be discharged or directed into the storage receptacle, and the said gas under unequal pressure in the storage receptacle may be delivered to the wind instrument at a substantially uniform 100 pressure, for the purposes stated.

105

2. In a device of the class described, the combination of an engine exhaust pipe, an inelastic gas storage receptacle in communication with the exhaust pipe, said exhaust pipe being provided with an outlet other than the one leading to the storage receptacle, a manually operated valve device whereby the exhaust gases may be directed either into the storage receptacle or through 110 said outlet, a check valve interposed between the exhaust pipe and the storage receptacle to prevent the flow of gas from the storage receptacle to the exhaust pipe, a pressure equalizing receptacle, there being a restricted passageway provided between 115 said receptacle and the storage receptacle, and a wind instrument operatively connected with the equalizing receptacle, the passageway from the equalizing receptacle to the 120 wind instrument being unobstructed, whereby gas under fluctuating pressure in the exhaust pipe may either be discharged or directed into the storage receptacle, and the said gas under unequal pressure in the storage receptacle may be delivered to the wind instrument at a substantially uniform 125 pressure, for the purposes stated.

130

the wind instrument being unobstructed whereby gas under fluctuating pressure in the exhaust pipe may either be discharged or directed into the storage receptacle, and the said gas under unequal pressure in the storage receptacle may be delivered to the wind instrument at a substantial uniform pressure, and a suitable valve arranged between the check valve and the storage re-

ceptacle to relieve excessive pressure within 10 the storage receptacle.

In testimony whereof I affix my signature, in presence of two witnesses.

ALVA WILLIAMSON.
